US00D797957S

(12) **United States Design Patent** (10) **Patent No.:** **US D797,957 S**
Larson (45) **Date of Patent:** **** Sep. 19, 2017**

(54) **FLOOR UNDERLayment**(71) Applicant: **PROGRESS PROFILES SPA**, Asolo (TV) (IT)(72) Inventor: **David D. Larson**, Golden, CO (US)(73) Assignee: **PROGRESS PROFILES S.P.A.** (IT)(***) Term: **15 Years**(21) Appl. No.: **29/547,874**(22) Filed: **Dec. 8, 2015****Related U.S. Application Data**

(60) Division of application No. 29/493,206, filed on Jun. 6, 2014, which is a continuation of application No. 12/550,111, filed on Aug. 28, 2009, now Pat. No. 9,188,348.

(51) **LOC (10) Cl.** **25-01**(52) **U.S. Cl.**USPC ..... **D25/160**(58) **Field of Classification Search**

USPC ..... D25/138, 139, 140, 141, 143, 144, 145, D25/146, 147, 148, 149, 151, 152, 153, D25/154, 155, 156, 157, 158, 159, 160, D25/161, 162, 163, 142, 115, 118; D5/1, D5/2, 4, 39, 58, 61, 63, 3 CPC E04B 5/00; E04B 2001/1984; E04B 2001/2484; E04F 15/00; E04F 15/02; E04F 15/02044; E04F 15/0215; E04F 15/18; E04F 15/182; F24D 3/02; F24D 3/12; F24D 3/14; F24D 3/142; F24D 3/149; F24D 13/02; F24D 13/024

Primary Examiner — Vy Koenig*Assistant Examiner* — Kimberly Barnes*(74) Attorney, Agent, or Firm* — Sheridan Ross P.C.(57) **CLAIM**

The ornamental design for a floor underlayment, as shown and described.

DESCRIPTION

FIG. 1 is a perspective view of a floor underlayment in accordance with the present invention;

FIG. 2 is a top plan view of the invention illustrated in FIG. 1;

FIG. 3 is a side elevational view of the invention illustrated in FIG. 1; and,

FIG. 4 is a bottom plan view of the invention illustrated in FIG. 1.
